UNITED STATES PATENT OFFICE.

EDWARD E. CARR, OF CHALMERS, INDIANA.

ELECTRIC BURGLAR-ALARM.

SPECIFICATION forming part of Letters Patent No. 357,815, dated February 15, 1887.

Application filed June 1, 1886. Serial No. 203,851. (No model.)

To all whom it may concern:

Be it known that I, EDWARD E. CARR, of Chalmers, in the county of White and State of Indiana, have invented a new and useful Improvement in Electric Burglar-Alarms, of which the following is a specification.

My invention relates to electric burglar-alarms which are designed to be applied to doors and windows of dwellings, barns, stables, or other buildings in such a manner that the surreptitious raising of a window or opening of a door shall be made to break an electric circuit and sound a continuous alarm on a bell.

15 My invention consists in the peculiar arrangement of the circuit and contacts and means for locating the break, which I will now proceed to fully describe.

Figure 1 is a front elevation of the alarm-board, showing the battery-connections and the electric circuits. Fig. 2 is a sectional view of a window sash and frame, showing the means for breaking the circuit by the raising of the window. Fig. 3 shows a modified 25 means for breaking circuit as applied to a door.

In the drawings, A represents an electrical bell of that pattern in which the electric circuit is alternately made and broken to sound a continuous alarm. For this purpose the battery B is connected for the vibrating circuit with the binding-post *i* by wires *k m*, and with binding-post *j* by wires *n o*. From binding-post *i* a wire leads to the magnets *a a*, and from the magnets to the adjustable contact *f*, and from this contact to spring *e* on the armature *b*, through the armature to spring *h*, and thence to the binding-post and the other pole of the battery. The action of this vibrating bell is 30 as follows: When the current is completed through the circuit, thus described, the armature *b* is attracted, and the hammer *c* carried thereby is made to strike the bell. As the armature is thus attracted the spring *e* is made 35 to leave the contact *f*, and the current being broken the armature flies back again from the tension of the spring *h*, which thus re-establishes the circuit and gives another stroke on the bell. This is the ordinary form of vibrating 40 bell. In connection with the circuit thus de-

scribed another wire, *p q*, connects with the contact *f* of the bell, and this wire, together with *k m n*, forms the long circuit, or the circuit in which the several circuit-breakers are placed, which are designed to be placed at the doors and windows of the house to secure the same, and all of which are contained in the circuit *k m n p q*, which is a normally-closed circuit, and which holds the armature *b* away from the contact *f*, so that the short vibrating circuit is not completed as long as the long circuit is unbroken. As soon, however, as the long circuit is broken by the raising of a window, opening of a door, or cutting of the wire, the vibrating circuit is established and a continuous alarm is rung upon the bell.

In order to have the requisite number of circuit-breakers for the different windows and doors of a house and keep them all under inspection at a single point, I employ a series of 70 plates, *C C' C² C³*, which are parallel with but insulated from each other, and connecting with these plates are a series of loops, *E E' E²*, each of which loops has a circuit-breaking device, *F F' F²*, &c., in the same, which is adapted to 75 be fitted into a window or door, so as to be operated by the opening of the same. These circuit-breakers consist simply of two springs, *S S'*, insulated from each other and held in a frame, *t*, which springs are normally in contact when the 80 springs are pressed together by the window when closed, and which, when relieved of pressure, separate and break the circuit. In fitting this circuit-breaker to the window, Fig. 2, its frame *t* is screwed into the window-frame, 85 with the bend of one of the springs, *S*, projecting toward the edge of the sash, and the upper part of the edge of the sash by bearing against this bend forces the two springs in contact. The principal portion of the edge of the 90 sash below the upper part is channeled or grooved, so that as soon as the sash is raised the bend of the spring *S* flies into the groove, and thereby breaking the contact between springs *S S'* opens the long circuit and permits the vibrating circuit to act and sound an alarm. It will thus be seen that when the circuit-breakers *F F' F²* are in place in the windows and the windows closed the current of 95 the long circuit passes down from one plate, 100

C, to the circuit-breaker F, and up thence to the plate C', then down again to the circuit-breaker F' in another window and back to the next plate, C², and so on, and as soon as any of the circuit-breakers open, from the surreptitious opening of the window or door, the vibrating current is established and the alarm given. Now, to locate the break from any given central point, the plates C C', &c., are arranged as an indicator, and a metal pin, D, is constructed so as to be inserted in holes between the plates, and by touching both adjacent plates to connect the same, so that when an alarm is sounded the pin D is successively inserted in the several holes between the different plates, and when its insertion stops the alarm this serves to indicate the fact that the window was opened whose circuit-breaker is in connection with the two plates between which the pin is inserted, for the reason that the pin re-establishes the long circuit which was broken at the window, and thus permanently breaks the vibrating circuit. It is easy, therefore, by placing suitable numbers or distinguishing marks over these plates to locate the break made by a burglar.

In adapting the circuit-breakers F to doors they may be placed either in the hinge-joint or at the lock-joint; but I prefer to locate them at the hinge-joint, and construct them as shown in Fig. 3, in which the hinge itself is employed by boring a hole in one leaf and placing an insulated screw therein, which is connected to one wire, and connecting the other wire to the leaf of the hinge, so that when the door is opened it passes off the insulated screw, and when closed comes in contact with the same.

For rendering the alarm inoperative, I place in the circuit-wire k m (which forms part of both the long and the vibrating circuit) the plates l l', which are insulated or disconnected from each other, except when the metal pin l' is inserted in a hole between the same. By taking out this pin it will be seen that both the long circuit and the vibrating circuit are permanently broken, and the doors and windows may thus in the day-time be opened and

shut without sounding the alarm. A similar pair of detached plates, r r', with hole between them and detachable pin r², is interposed in the branch p q of the long circuit, the object of which is to permit the long circuit to be broken at the instrument for the purpose of regulating or adjusting the vibration of the bell-ringing mechanism.

From the foregoing description it will be seen that only a single battery is used for both circuits, and the same wire k m n forms a part of both the long and the vibrating circuit. When the long circuit extends to a barn or other outbuilding, there is employed a ground-wire at each end to complete the circuit through the earth.

I am aware of the fact that an electric alarm-bell has been combined with a short circuit for sounding a continuous alarm, and a long circuit, which, when broken by the opening of a door or window, allows the short circuit to be operated, and I am also aware that a series of switch-plates for testing and locating the break in the long circuit is not new, and I therefore only claim the particular combination and arrangement of the parts shown and described.

Having thus described my invention, what I claim as new is—

The combination, with the electric bell and battery connected by both a long and short circuit, as described, of the series of insulator-plates C C' C² C³, the wires p q, connected with the first plate, C, and having cut-out mechanism r r' r² in their circuit, the wire o, connecting the last plate, C³, to the bell-frame, the double-circuit wires k m n, connecting said last plate, C³, to the bell-magnets and having cut-out mechanism l l', and battery in their circuit, the series of wire loops E E' E², having their terminals connected to different ones of the plates C C' &c., and the circuit-breakers interposed in the loops, substantially as shown and described.

EDWARD E. CARR.
